UNITED STATES PATENT OFFICE.

HARLEY S. JOHNSON, OF ERWIN, TENNESSEE.

PENCIL CLIP.

Application filed April 7, 1927. Serial No. 181,826.

This invention relates to pencil clips and more particularly to a device of this character supporting a knife blade.

- An important object of the invention is to 5 provide a device of this character, in which the mounting of the knife blade thereon is such that the blade may not be at any time accidentally opened or opened while in position upon the pencil.
- 10 A further object of the invention is to provide means whereby the blade will be relatively securely held in its operative position.

These and other objects I attain by the construction shown in the accompanying drawings, wherein for the purpose of illustration is shown a preferred embodiment of my invention and wherein:

Figure 1 is a side elevation showing a combined pencil clip and knife constructed in accordance with my invention applied to a pencil;

Figure 2 is an elevation at right angles to the view shown in Figure 1;

Figure 3 is a longitudinal sectional view therethrough, the knife being in the open position;

Figure 4 is an end elevation partially broken away.

Referring now more particularly to the drawings, the numeral 10 indicates a tubular barrel adapted to receive the pencil and having one end thereof slotted at 11 to produce fingers 12, which are inbent to resiliently grip a pencil passed through the barrel. The opposite end of the barrel is provided with diametrically opposed ears 13, apertured, as at 14. One of the slots 11 disposed upon a diameter at right angles to the diameter upon which the ears 13 are arranged is elongated, as at 15, for a purpose presently to appear.

The numeral 16 generally indicates a blade support arcuately curved with an internal curvature similar to that of the exterior of the barrel 10. This support is slightly more than semi-cylindrical and has projecting inwardly therefrom at points equally spaced from its side edges pivot lugs 17 which are arranged upon the diameter of the support and are adapted to enter the apertures 14 of the ears 13. These lugs are preferably formed by the inturned end portions of an arcuately curved band 18 which are secured to and form a reinforcement for the wall of the support. At one end, the support has projecting therefrom a knife blade 19, which is rigidly se-

cured thereto and which, when the support is in applied position and arranged at that side of the tube 10 having the slot 15, has its cutting edge extended into said slot.

It will be obvious that the extension of the edges of the support beyond the diameter will cause this support to frictionally engage with the walls of the tube as the support is swung from one side to the other of the tube and resist such movements until they are nearly completed when the extended portions will spring over the wall of the barrel and firmly hold the support in its new position.

The slotted end of the barrel 10 is provided with an integral extension 20 forming a clip 60 for engagement over the outer wall of a pocket, within which the pencil, to which the device is applied, is inserted. The outer face 65 of this extension is preferably constructed to 70 form a nail file, as indicated at 21.

It will be obvious that a device of this character may be carried with safety and will provide a convenient knife blade for use in sharpening pencils and the like. The extension or clip 20 provides an extension of the 75 effective length of the tube, such that it may be conveniently handled.

Since the construction hereinbefore set forth is obviously capable of a certain range 80 of change and modification without materially departing from the spirit of the invention, I do not limit myself to such specific structure except as hereinafter claimed.

I claim:

1. In a pencil clip, a tube adapted to receive and frictionally hold a pencil and through opposite ends of which the pencil may extend, an arcuately curved blade support pivoted intermediate its ends to one 90 end of the tube and swingable about said end of the tube to positions where it substantially aligns with the tube and either end thereof extends outwardly from the tube, a knife blade secured to and extending outwardly 95 from one end of the support and means for frictionally holding the support in either of said positions.

2. In a pencil clip, a tube adapted to receive and frictionally hold a pencil and 100 through opposite ends of which the pencil may extend, an arcuately curved blade support pivoted intermediate its ends to one end of the tube and swingable about said end of the tube to positions where it substantially 105 aligns with the tube and either end thereof extends outwardly from the tube, a knife 110

blade secured to and extending outwardly from one end of the support, the wall of the tube having a longitudinally extending slot receiving the edge of the knife blade when

5 in one of said positions.

3. In a pencil clip, a tube adapted to receive and frictionally hold a pencil, an arcuately curved blade support pivoted intermediate

10 its ends to one end of the tube and swingable about said end of the tube to positions where it substantially aligns with the tube and either end thereof extends outwardly from the tube, a knife blade secured to and extending outwardly from one end of the support,

15 the edges of said support being spaced apart a distance less than the external diameter of the tube.

4. In a pencil clip, a tube adapted to receive

and frictionally hold a pencil and through opposite ends of which the pencil may extend, 20 an arcuately curved blade support pivoted intermediate its ends to one end of the tube and swingable about said end of the tube to positions where it substantially aligns with the tube and either end thereof extends outwardly from the tube, a knife blade secured to and extending outwardly from one end of the support, the edges of said support being spaced apart a distance less than the 25 external diameter of the tube, said tube having a slot receiving the cutting edge of the blade when in one of said positions.

In testimony whereof I hereunto affix my signature.

HARLEY S. JOHNSON.
